UNITED STATES PATENT OFFICE.

MELVIN L. SEVERY, OF ARLINGTON HEIGHTS, MASSACHUSETTS.

ELECTRIC SOUND-PRODUCER.

1,190,332.

Specification of Letters Patent. Patented July 11, 1916.

Application filed February 18, 1907. Serial No. 357,977.

To all whom it may concern:

Be it known that I, MELVIN L. SEVERY, a citizen of the United States, and residing at Arlington Heights, in the county of Middlesex and Commonwealth of Massachusetts, have invented certain new and useful Improvements in Electric Sound-Producers, of which the following is a full, clear, and exact description.

This invention relates to that class of instruments wherein sounds, and particularly musical ones, are produced through the effect of electric influences upon a sonorous body; and it consists essentially in means whereby a translating device, such as a telephone receiver, may emit musical sounds through the effect of a variable section of relatively poor conductivity acted upon by a rotating means for varying the amount of current traversing said variable section.

My invention further consists in the construction of practical and efficient means for applying the foregoing to the production of music in either a key-operated instrument, or an automatic player, and also to telegaphonic or phonographic reproduction.

Referring to the drawings forming part of this specification, Figure 1 is a diagram illustrating the simplest form in which I have embodied my invention. Fig. 2 shows the invention arranged to be used in connection with a plurality of translating devices. Fig. 2^a is an end elevation of the timbre-form drum and forms, the latter broken away to show their differing peripheries. Fig. 3 is an elevation, partly in section, showing the invention provided with means for changing the overtones of the sonorous vibrations communicated to the translating devices. Fig. 4 sets forth another method of changing at will the quality of the sonorous vibrations produced by the instrument. Fig. 5 is a detail sectional view showing one of the devices used in this last referred-to construction. Fig. 6 is a side view of one of the stops for throwing into circuit any one or more sets of said devices. Fig. 7 is a cross section of the same. Fig. 8 is a diagram, partly in perspective, showing my arrangement for nullifying the broken effect of an uneven or fractional number of timbre-crests. Fig. 9 shows certain modifications of the timbre-forms and points coacting therewith. Fig. 10 shows other modifications of the same. Fig. 11 is a face view of a disk provided with rings located upon its

flat face, which may be disposed as timbre-forms. Fig. 12 is a sectional view of the same. Fig. 13 is a diagram of a plurality of translating devices adapted to simultaneously reproduce a variety of tone-qualities. Fig. 14 is a sectional view of a construction in which each note has its own source of power and translating device. Fig. 15 is a sectional view illustrating a preferred mode of mounting, spacing, and insulating the annular timbre-forms.

In the construction set forth in Fig. 1, the reference numeral 1 designates a disk of thin sheet metal uniformly rotated with its periphery in proximity to the end of a fixed point or terminal 5; while 6 is a key by means of which to close the circuit between said disk and point or terminal 5. The latter consists of the magnet 7 and diaphragm 8. A coil 12 is introduced into this circuit for intensifying the discharge. The periphery of the disk 1 being wavy or radially irregular, the electric discharge between the same and the point or terminal 5 will vary in a corresponding manner; the nearer they are together at any instant, the stronger being such discharge. These variations in current-strength being transmitted to the magnet 7, the diaphragm 8 will be correspondingly affected; and the speed of the disk's rotation being made such as to present a sufficient number of crests to the point or terminal 5 per second, said diaphragm will emit a musical note, the pitch of which depends on the disk's speed, and the quality of which will depend on the shape of the undulations on said periphery. This undulatory peripheral edge of the disk 1 term a timbre-form; the same being preferably the resultant curve produced by combining with a fundamental the vibrational forms of its overtones, as more particularly described in my companion application, Serial No. 357,978, now replaced by application Serial No. 756,169. When the disk 1 is revolving in the air or other high resistance gas, it is necessary to introduce an induction coil 12 in the circuit in order to insure the proper discharge of the current from the disk-edge to the point or terminal 5. This induction coil is of a well-known type, comprising a primary coil of short thick wire and a secondary coil of long thin wire. A high frequency circuit-interrupter 12^a is provided in the primary circuit, and this interrupter may be such as is used in wireless tele-

raphy, that is, one which interrupts the primary circuit very rapidly to produce a high tension current in the secondary circuit. This portion of the apparatus is operative if 5 any source of high tension current is employed, such as is obtained by the use of a Ruhmkorff coil, a static machine, or any other suitable high tension source. The object of an induction coil is to provide a current of sufficient electromotive force to readily leap the air-gap between the point 5 and the disk 1. To further assist the same, a fine wire 130 may be located beneath the gap between such edge and point, kept heated by 10 current from a source 131 or otherwise, in order to warm the air or gas thereat and increase the conductivity of the latter.

Instead of a disk, I may use an annulus or washer mounted on a drum 10, as shown in 15 Figs. 2, 3, 5, 14 and 15 as a more commercial form; an entire disk of sheet metal being not only more expensive, but liable to spring laterally.

In Fig. 2 is shown another method of producing a rich musical tone. Here, I group 20 together four disks or timbre forms 1^a, 1^b, 1^c, 1^d for the production of a single composite note. For instance, the group C has its points or terminals 5 wired to a single key 25 6 C; the group E has its points wired to the E key, and so on; the arrangement of each group being as follows: The first, or one of, the timbre forms is peripherally arranged 30 with such a form of curve as acting alone 35 will yield the fundamental of the note desired; another timbre form will give the first harmonic; another, the second harmonic, and the fourth, the third harmonic. All four sets of vibrations being simultane- 40 ously communicated to the translating device or telephone, a rich note is the result, and one embracing all the overtones or harmonics ordinarily desired. In the same 45 manner, a larger number of disks can be employed in a group, and an increased variety of harmonics given to each note. Another construction shown in the same figure is that 50 by which a separate telephone is employed for each note of like letter. In other words, one receiver will be used for all the C-notes; another for all the D-notes, and so on. This produces a richer effect than when all the notes are emitted by a single telephone receiver. As illustrated the C' group of timbre 55 forms are wired to the C' key, and the C' key has its underlying contact wired to the wire 14 which joins the C-key contact to the 8 C receiver, and so on.

In Fig. 3 is shown an improved means for 60 rendering the gaps between the timbre forms 1 and their respective points or terminals 5 somewhat better conductors than is done by the warmed air or gas above described. This consists of a liquid, such as 65 water rendered somewhat conductive, with-

in which the rotating timbre forms are located. To do this, the drum 10 is located in a vessel 30, preferably cylindrical and vertical, and either formed of a non-conducting material, or having its inner surface non-conducting. Through the sides of this vessel project the points or terminals 5 suitably insulated therefrom, and having their inner ends preferably flush with the vessel's inner surface in order to present less obstruction to the rotation of the liquid within the vessel. This is not essential, but its object is to insure that no eddies or small vacant spaces shall be formed between the timbre-form edges and the points or terminals 5. To insure that the rapid rotation of the liquid within the cylinder 30 shall not throw the former out, the cylinder is closed by a cover 31, and a constant pressure maintained by a pipe 32 bringing liquid from a height, or otherwise.

Inasmuch as the rotating timbre forms associated with a single tone are, as shown in the figure, not adapted for easy alteration, I have devised means whereby their relationship to each other can be so changed at will as to entirely alter the resultant tone-quality. By diminishing the loudness of the vibrations produced by one timbre-form of a group, and increasing the loudness of those of a second, while the other two, for instance, remain equal, the resultant effect is quite different. To enable the operator on this instrument to produce any such different combinations at will throughout all 10 or any section of the notes of the key-board, I join all the fundamental timbre forms,—the lowest one in each group,—to the resistances 16 by wires 15; all the second timbre forms of each group by wires 15^a to the resistances 16^a; the third, by wires 15^b to the resistances 16^b, and the fourth by wires 15^c to the resistances 16^c. By moving the brushes 17 along said resistances, each set of brushes being preferably shifted equally 11 by the movement of a stop 18 common thereto, the lessened or increased resistance thus put into or cut out of each circuit, permits practically any desired variations in the strength of the harmonics of all the notes. 11

The circuit for above described arrangement comprises the current-source 24, wire 25, brush 4, shaft 3, drum 10 or any other conductor joining said shaft to the timbre forms, thence through any of said forms according to the key depressed, across the gaps through the liquid or electrolyte in the cylinder 30 to the nearest terminal point or points 5, through wires 15, 15^a, 15^b or 15^c, resistances 16, 16^a, 16^b or 16^c, brushes 17, 12 17^a, 17^b, or 17^c, wires 19, 19^a, 19^b 19^c, resistances 20, brushes 21, wire 22, magnet windings 7, and wires 23 back to the current-source 24. By having the wires 19^c joined to the wires 19^b, and the latter joined 13

to the wires 19^a, and 19^a to 19, the depression of a single key causes the current to traverse, in the construction shown, all four timbre-forms of a group simultaneously, 5 and so produces the rich tone desired.

By mounting the magnets 7 upon the lever 28 and depressing the pedal 27 in opposition to the tension spring 29, said magnet is moved closer to the diaphragm 8 and 10 thereby made to more strongly affect the latter and to increase the volume of sound accordingly.

Another, and much more simple method of accomplishing the above described change 15 in timbre of the instrument, is that illustrated in Figs. 4 to 7. This is based upon the fact discovered by me that the nearer the points or terminals 5 are to the forms 1, the louder the sound emitted. Hence by 20 varying such distances among the points of a group, and duplicating these differences throughout the compass of the instrument, a particular quality is yielded thereby. By having a plurality of such arrangements, 25 each with its own special timbre, and a stop for throwing it into and out of operation, a wide range of qualities is provided for the instrument. The most practical method of constructing these points 5 consists in 30 stamping those of each group from sheet metal, as shown in Fig. 5, where 50 designates a single member formed with several points or terminals of different lengths. These members 50 can be duplicated in large 35 numbers with but slight expense, and so insure a similarity of quality throughout the entire compass of the instrument. By providing the cylinder 30 with several sets of such point-members 50, each set extending 40 throughout a part or the whole of the range of the instrument, but the different sets adapted for unlike qualities, and switching any one or more of such sets into circuit at will, the instrument is given a wide range 45 of timbre. To switch any set of said members 50 in or out, each point-member is furnished with a spring-contact 34 rigidly held at one end and having its opposite end normally out of touch with a contact-bar 35, 50 as shown in Figs. 4, 6 and 7. Beneath these contacts are longitudinally movable rods 36 equal in number to the different sets of members,—shown in Fig. 7 as three. On these rods are suitably proportioned wedge-projections 37 so located thereon that, when any rod is drawn lengthwise a specified distance, all the contacts pertaining to a single set of point-members will be raised into touch with the contact-bars 35. Now, a certain 55 rod 36 having been moved and the appropriate spring-contacts 34 put thereby into touch with the bars 35, when the keys 6 are depressed one of the three qualities of music will be produced. When this rod has been 60 returned and a second rod drawn outward, 65

a second quality of music will be produced; and so with the third rod. By drawing out two of said rods at the same time, a combination of two qualities is produced when the keys are manipulated; while a movement of all three rods enables a combination of all three qualities to be possible. 70

It is impossible for the vibrational-crests of a timbre form to meet accurately about its periphery throughout the entire octave 75 of such forms, where all are rotated upon a common shaft, owing to the fractional nature per unit of time of certain notes. Consequently there will occur a break at certain points in some of the notes. To remedy this, 80 such fractional timbre forms are each provided with two diametrically opposite points or terminals 5, 5^a, as shown in Fig. 8, each wired to a separate translating device 7 and provided with means for automatically intensifying the vibrations given through one point to its translating device while diminishing the vibrational strength given to the other translating device through the other point. In accomplishing this, the 85 key 6 for such timbre form is given two brushes 21 21^a moving along two separate rheostats 20 20^a; and a portion of the circuit for each point consists of two annular layers of compressed graphite uniformly rotated. 90 These annular layers of compressed graphite 41, 41^a are put into circuit by brushes 47, 47^a joined by wires 48, 48^a to the brushes 21, 21^a respectively. The terminals of the shaft 44 by which said annular resistances are rotated, are insulated one from the other and given brushes 45, 45^a joined by wires 46, 46^a to the electromagnets 7, 7^a. From each shaft-terminal runs a wire 43, 43^a to one of the annular layers, such wires touching the 100 latter at diametrically opposite points. As a result of this last-described arrangement, when the point of contact of the brush 47 is diametrically opposite to the juncture of the wire 43 with the annular layers 41, the 105 shortest path of the current is through an entire semi-circumference of the same. At the same instant the brush 47^a is practically touching the wire 43^a and substantially no obstruction is given to the current. Hence, 110 when one translating device is receiving its maximum of current and so responding its loudest, the other translating device is receiving its minimum of current and accordingly responding its feeblest. When the 115 drum carrying said annular layers of compressed graphite has reached a point in its rotation 90° from this position, less than the maximum resistance is given to each current, and the two translating devices are 120 sounding with equal but less than maximum strength. But their combined effect is equal to the maximum of one alone, and so the sound produced remains constant. By timing the rotation of the annular layers of 125 130

compressed graphite in unison with that of the timbre form 1, but with the abnormal undulation 2' disposed to reach one of the points or terminals, as 5^a, simultaneously with the descent of the wire 43 to its farthest from the brush 47, it results that the passage of the break or abnormal undulation occurs when its resonant translation is at its feeblest. Hence such break becomes ¹⁰ perceptible.

I have thus far described the timbre forms as undulatory in character, but I have discovered that it is possible to produce similar effects with sharp points or abrupt cog teeth, as illustrated in Fig. 9. The undulatory, or graduational effect is caused by prolonging peripherally the points or terminals, as 5^b or 5^c. By curving the edge of the point or plate 5^b as shown, in Fig. 9, the gradually increasing strength of current passing while a cog 2^b is approaching the center point of the said curved edge, and its gradually diminishing strength as such point is passed, can be arranged to closely approximate if not accurately reproduce all the undulatory character desired. By having said edge somewhat irregular, various overtones can be produced in the resultant music.

Instead of employing disks or washer-shaped members 1, a smooth surfaced cylinder 100 can be used for the same purpose. For instance, the cylinder may be of metal or other conducting material surrounded with an insulating coating cut through at uniform intervals to expose the conducting surface. Fig. 10 shows such a cylinder having four different kinds of exposed intervals, as diamond shaped spots, undulatory continuous, circular, and laterally elongated. With the first two, simple lineal points or terminals 5 may be used; but other forms are preferable for the other two, as the oblique plate 5^a, or the annular 5^b.

I do not restrict myself to a cylindrical rotating member, as the timbre forms may be located on the flat faces of disks, as 101, in Figs. 11 and 12, and on the tapes shown in copending application Serial No. 756,169.

When the annular disks 1 are used, of the type shown in Figs. 2, 3 and 4, it is necessary or at least far better to insulate all but the peripheral edges thereof, in order to prevent current-leakage from other parts of the rotating members. A good way in which to do this is by locating a washer 102 of suitable insulating material between each pair of annular disks. This not only insulates the inner surfaces of the annular disks, but accurately positions them upon the cylinder 10, as shown in Fig. 15.

In the construction illustrated in Fig. 13, are two translating devices 7 connected with timbre-members 50 of different qualities, and provided with switching rods 36 and plate 35 similar to what is set forth in

Figs. 4 to 7, in order that either or both together of the different tone-qualities may be sounded. This enables the performer to render at will an organ or piano accompaniment to a violin solo, for instance.

Fig. 14 shows an arrangement wherein each note, or each note of similar letter throughout the key-manual, has a translating device and a current-source of its own. The advantage of this is that there is no ⁷⁰ diminution in loudness when many notes are sounded simultaneously.

It should be understood that I may use any desired number of overtones or partials to each note, and that I may use a different ⁸⁰ number for the same letter of the scale in different parts of the key-board.

What I claim as my invention and for which I desire Letters Patent is as follows, to wit:—

1. An electric musical instrument comprising a vibrating body, electrical means for its vibration, a source of current, a circuit including said means and source and having a fluid slightly conductive section, a rotatable member located in said fluid section, and means connected with said member for producing by the latter's motion pulsations in the current flowing through said fluid section.

2. An electric musical instrument comprising a vibrating body, electrical means for its vibration, a source of current, a circuit including said means and source and having a fluid slightly conductive section, a current varying means including a rotatable member extending into said fluid, and means for producing by the motion of said member pulsations in the current passing through said fluid section between said member and a fixed point of said circuit.

3. An electric musical instrument comprising a vibrating body, electrical means for its vibration, a source of current, a circuit including said source and means and having a fluid slightly conductive section, and a rotatable circular member extending into said fluid and formed with an undulatory periphery; said member forming a part of said circuit and acting by its rotation to produce pulsations in the current passing through said fluid between said member and a fixed point in the circuit.

4. An electric sound producing instrument comprising a vibrating body, electrical means for its vibration, a source of current, a circuit including said source and means and having a fluid slightly conductive section, and a plurality of rotatable circular members extending into said fluid and forming a part of the circuit; said members being formed with peripheral projections spaced for the production of different overtones of the same musical note.

5. An electric sound producing instru-

ment comprising a vibrating body, electrical means for its vibration, a source of current, a circuit including said source and means and having a fluid slightly conductive section, a plurality of rotatable circular members extending into said fluid and forming a part of the circuit, and means for introducing different resistances into the circuits of said members; said members being formed 10 with peripheral projections spaced for the production of different overtones of the same musical note.

6. An electric musical instrument comprising a vibrating body, electrical means for its vibration, a source of current, a circuit including said source and means and having a fluid slightly conductive section, a plurality of sets of circular members rotated in said fluid, and means for introducing different resistances into the circuits of said members; each set of members being formed 20 with peripheral projections spaced for the production of different overtones of the same musical note.

7. In an electrical sound-producing instrument, the combination of a vibrating body; electrical means for its vibration; a source of electric current; a circuit including said means and source and containing a 25 fluid section; and a movable member located in said fluid section and having an undulating periphery for producing during its movement pulsations in the current flowing through the fluid gap or section between said movable member and a proximate section of the circuit.

8. In an electrical sound-producing instrument, the combination of a vibrating body; electrical means for its vibration; a 30 source of electric current; a circuit including a conductor said means and source, and containing a fluid section; a movable member located in said fluid section, and having an undulating periphery for producing during 35 its movement pulsations in the current passing through said fluid section between said member and a fixed portion of the conductor; and means for varying the conductivity of the fluid medium in the space between said movable member and said fixed portion of the conductor.

9. In an electrical sound-producing in-

strument, the combination of a vibrating body; electrical means for its vibration; a source of electric current; a circuit including a conductor said means and source, and containing a fluid section; a movable member located in said fluid section, and having an undulating periphery for producing during 40 its movement pulsations in the current passing through said fluid section between said member and a fixed portion of the conductor; and means for heating and thereby varying the conductivity of the fluid medium in the space between said movable member 45 and said fixed portion of the conductor.

10. In an electrical sound-producing instrument, the combination of a vibrating body; electrical means for its vibration; a source of electric current; a circuit including a conductor said means and source, and containing a fluid section; a movable member located in said fluid section, and having an undulating periphery for producing during 50 its movement pulsations in the current passing through said fluid section between said member and a fixed portion of the conductor; and an electric heating device for varying the conductivity of the fluid medium in the space between said movable 55 member and said fixed portion of the conductor.

11. In an electrical musical instrument, the combination of a plurality of vibrating bodies; electrical means for their vibration; a source of electric current; branch circuits including said electrical means, and each containing a plurality of conducting terminals and a fluid section; and a plurality of 60 groups of members revoluble in said fluid and each forming a part of one of said circuits, said members having undulating peripheries spaced from proximate terminals, to produce in the circuits pulsations of frequencies to educe from the vibrating bodies 65 their respective fundamental tones and selected overtones.

In testimony that I claim the foregoing invention, I have hereunto set my hand this 24th day of December, 1906.

MELVIN L. SEVERY.
